CLAIM

The ornamental design for a pendant or charm, as shown and described.

DESCRIPTION

FIG. 1 is a top plan view of a pendant or charm showing my new design;

FIG. 2 is a front elevational view;

FIG. 3 is a left side elevational view;

FIG. 4 is a right side elevational view;

FIG. 5 is a rear elevational view;

FIG. 6 is a bottom plan view;

FIG. 7 is a top plan view of a pendant or charm showing a second embodiment of my new design;

FIG. 8 is a front elevational view thereof;

FIG. 9 is a left side elevational view thereof;

FIG. 10 is a right side elevational view thereof;

FIG. 11 is a rear elevational view thereof;

FIG. 12 is a bottom plan view thereof;

FIG. 13 is a top plan view of a pendant or charm showing a third embodiment of my new design;

FIG. 14 is a front elevational view thereof;

FIG. 15 is a left side elevational view thereof;

FIG. 16 is a right side elevational view thereof;

FIG. 17 is a rear elevational view thereof; and

FIG. 18 is a bottom plan view thereof.
